(57) **CLAIM**

The ornamental design for a magnetic adapter for a universal shaft sensor mount, substantially as shown and described.

DESCRIPTION

FIG. 1 is a perspective view.

FIG. 2 is a top view.

FIG. 3 is a bottom view.

FIG. 4 is a peripheral view; and,

FIG. 5 is a peripheral view taken 90° from FIG. 4.

1 Claim, 1 Drawing Sheet

FIG. 3

FIG. 2

FIG. 4

FIG. 5

FIG. 1
